RAILWAY PASSENGER CAR

Walter B. Dean, Narberth, Pa.

Application July 10, 1956, Serial No. 42,198

Term of patent 14 years

(Cl. D66—1)

Fig. 1 is a side elevation of a railway passenger car showing my new design; and

Fig. 2 is a side perspective view of the other side of the car.

The essential features of the design reside in those portions shown in full lines.

I claim:

The ornamental design for a railway car, substantially as shown and described.
